UNITED STATES PATENT OFFICE.

CHARLES MUNTER, OF NEW YORK, N. Y.

BODY-STABILIZER.

1,342,566.

Specification of Letters Patent.

Patented June 8, 1920.

Application filed October 18, 1918. Serial No. 258,686.

To all whom it may concern:

Be it known that I, CHARLES MUNTER, a citizen of the United States, residing in the city of New York, borough of Manhattan, county and State of New York, have invented a certain new and useful Body-Stabilizer, of which the following is a specification.

This invention is a body stabilizer, designed to correct an improper poise of the body, or to preserve and improve a normal healthy poise. Accordingly it serves the purpose and function of both a preventive and corrective device for the purposes specified. Moreover, it accomplishes the results specified in a simple, scientific and harmless manner.

After years of exhaustive scientific study and measurement of inanimate skeleton frames and animate human forms, I have discovered that it is the displacement of the covering of the body, *i. e.*, the skin, which forces the body to change its contour and physical measurements, and that the contraction and expansion of the skin is dependent on the volume of air in the lungs.

After making accurate measurements of the bone structure, I was able to obtain exact measurements around those parts of the body that grew certain muscles, and by duplicating the measurements of the skin over those parts (which are the back, reaching almost up to the neck and extending downwardly to the lumbar region of the spine, under the arms and over the shoulders, and to the edge of the sockets that hold the arms in place), and by exactly duplicating these sections, I have been able to incase the bony structure in pliable material which holds the entire torso in its normally correct position. From a functional or mechanical standpoint, this result is accomplished by so balancing the body on the spine as to compel the lungs to breathe with their maximum capacity. By positioning this material firmly against the spine, and securely holding it in place by a support extending around the waist, with securing means in front of the body, the body is precluded from either sagging or drooping into an abnormal position, thereby inflating the lungs, poising the spine and forcing the head in a proper position, whereby the ribs are held up and out, and freeing the internal organs from all external pressure as well as preventing the abdomen from being forced abnormally outward.

The results specified are not attributable to the strength of the fabric employed or to the belt that holds it in place, but, in contradistinction, by the symmetrical reproduction, in the form of the garment of the natural covering, that not only holds the spine in a perfect poise, but prevents it from falling downwardly to the normal position of the shoulders, such falling downward being a prime cause of hollow lungs and sunken chest. Thus the garment prevents the sagging of the body by the assistance it gives to the lungs, and not by any inherent physical strength of the material from which the garment is made. By a peculiar cutting of the material, the back of the body of the wearer becomes shorter and the front becomes longer thereby causing the body to assume a correct poise and precluding it from sagging or drooping.

The accompanying drawings illustrate the preferred, practical embodiment of the invention, but the construction shown therein is to be regarded, merely, as a typical embodiment of the invention, and not as exclusive of other forms in which the invention may take expression.

Figure 1 shows the garment in position on the wearer, in substantially a three quarter position of the body;

Fig. 2 is a back view of the garment, when positioned on the wearer; and

Fig. 3 is a perspective view of the garment, looking toward the front thereof.

Referring to the drawings, 1 is the body of the garment, preferably made in one piece, of the general form shown, having the reentrant portion 2, and tapered downwardly, toward its lower end 3, near which is attached or otherwise associated, by sewing or otherwise, a belt 4 for securing the garment to the wearer. In the preferred embodiment of the invention the belt is formed in one piece, an intermediate portion of which extends across the lower portion of the back member and is non-adjustably and fixedly sewed thereto. The garment is so cut that there is provided at the upper part thereof, on either side, a strap 5, which extends over the shoulder and under the arm of the wearer, its end being attached, or detachably secured, at the side of the body of the garment, as shown at 6, in any suitable way, thereby forming the armholes.

As hereinbefore pointed out, the garment

is so cut and shaped as to snugly cover substantially the entire back of the wearer, extending as it does almost up to the neck and downwardly to the lumbar region of the spine, under the arms and over the shoulders, to substantially the edges of the sockets in which the arms articulate. It is, in effect, a replica of the true form of the body covering, or skin, on the surface covered by the garment, when the body is correctly poised.

The garment can be readily slipped on the wearer whereupon the belt is tightened to produce the desired tautness. The pressure or pull is applied to the waist line and in a forward direction. The effect of this pull, however, is to cause the shoulders to be thrown backward and outward, thereby assuming, together with the chest and stomach, correct anatomical positions. The spinal column is thereby locked in place, the body being thereby poised on the spinal column, and, while the individual vertebra can articulate normally and freely, they severally retain their correct position in the vertebræ. Moreover, the ribs of the wearer are forced forward to their natural position with reference to the sternum, thereby giving the heart, lungs and other vital organs entire freedom in the performance of their normal functions.

It will be understood that slight or formal changes may be made in the garment as described, and the resulting structure yet fall within the spirit and substance of the invention, the broad scope of which is commensurate with the appended claims.

Having thus fully described the invention, what I claim as new, and desire to secure by Letters Patent, is:

1. A body stabilizer embodying a flexible, non-adjustable, one-piece back member of substantially the same width as the back of the wearer and extending upwardly from the lumbar region to substantially the neck of the wearer, said back member being a substantial replica or contour of the subjacent skin of the wearer when the latter occupies a correct, anatomical poise, and a

pair of non-yieldable shoulder members, integral with the back member, extending upwardly from the back member over the shoulders and thence downwardly under the arms of the wearer with the ends of the shoulder members permanently secured to the lateral edges of the back member, in combination with a belt, the intermediate portion of which is non-adjustably and permanently secured to the back member above the waist line of the wearer, the free ends of which belt extend downwardly and forwardly around the body of the wearer and are adapted to be secured together at the front of the body and at substantially the waist line thereof to bind the back portion firmly to the figure and bring it into close fitting engagement with all portions of the figure of the wearer which it overlies.

2. A body stabilizer embodying a flexible, non-adjustable back member of substantially the same width as the back of the wearer and extending upwardly from the lumbar region to substantially the neck of the wearer, said back member being a substantial replica or contour of the subjacent skin of the wearer when the person occupies a correct, anatomical poise, and a pair of non-yieldable shoulder members, united to the upper portion of the back member, extending upwardly over the shoulders and thence downwardly under the arms of the wearer and being secured to the lateral edges of the back member, in combination with a belt securable to the back member, above the waist line of the wearer, the free ends of said belt extending downwardly and forwardly around the body of the wearer and being securable together at the front of the body at substantially the waist line thereof, whereby the back member of the garment is caused to be brought into close fitting engagement with all portions of the figure which it overlies.

In testimony whereof, I have signed my name to this specification.

CHARLES MUNTER.
